TUBE FRAME FOR AXMINSTER LOOMS

Elbridge R. Holmes, Worcester, Mass., assignor to
 Crompton & Knowles Loom Works, Worcester,
 Mass., a corporation of Massachusetts

Application February 12, 1938, Serial No. 190,256

2 Claims. (Cl. 139—10)

This invention relates to Axminster tube frames and the mechanism by which they are attached to the transporting chain of the loom.

Axminster tube frames ordinarily comprise an elongated bar from the lower end of which project a series of narrow tuft yarn tubes to receive threads unwound from a spool supported on the bar. These tube frames are transported by means of a pair of chains and are placed one at a time in transfer position where they are detached from the chains. The chains are ordinarily located behind and above the loom and pass over and under guide sprockets or pulleys so that the tube frames are first above and then below the chains.

It has been customary to attach the tube frame to the chains at points approximately aligned with the spool axis so that the greater part of the weight was disposed at one side of the chain. When passing from one side of a sprocket to the other, therefore, the attaching hooks are subject to considerable strain due to the fact that the weight is not balanced. It is an important object of my present invention to construct the tube frame and chain sprockets so that the connections between the tube frame and the chain are located at a point intermediate the longitudinal centers of the spool and the longitudinal bar. This construction requires a relative lowering of the chain with respect to the yarn spools and a modification of the attaching hook to cooperate with the chain in its new position. By this construction the turning force acting on the tube frame when the latter passes over a sprocket, for instance, is proportional to the difference between the weight of the spools and that of the bar.

I have found it possible to locate the chain and supporting hooks in such positions that one of these weights practically balances the other. This condition will exist when the transverse center of gravity, when produced longitudinally of the bar, passes through the chain, or between the top and bottom points of attachment between the chain and tube frame.

With these and other objects in view which will appear as the description proceeds, my invention resides in the combination and arrangement of parts hereinafter described and set forth.

In the accompanying drawing, wherein a convenient embodiment of my invention is set forth,

Fig. 1 is a front elevation partly in section of a tube frame and associated parts made according to my present invention.

Fig. 2 is a detailed vertical section on line 2—2 of Fig. 1.

Fig. 3 is a horizontal section on line 3—3 of Fig. 1.

Fig. 4 is an end view looking in the direction of arrow 4, Fig. 1, the clutch being omitted for the sake of clearness.

Fig. 5 is a view similar to Fig. 4 but on a reduced scale and showing the transporting chain carrying several tube frames.

Fig. 6 is a diagrammatic view setting forth the relation between the centers of gravity of the 10 yarn spools and the carrier bar with respect to the point of attachment of the tube frame to the transporting chain, and

Fig. 7 is a diagrammatic view showing the arrangement of the transporting chain and its 15 guide sprockets.

Referring to the drawing, the tube frame 10 comprises a hollow metallic bar 11 having top and bottom sections 12 and 13, respectively, and front and back walls 14 and 15, respectively. As shown herein the carrier bar is provided with a stiffening filler 16 which may be made of wood and there are attached to the front wall a series of depending yarn tubes 17.

Above the bar as shown in Fig. 1 is a yarn 25 spool S having a barrel 20 from which projects an end gudgeon 21 located on the longitudinal axis of the spool.

A clutch C is mounted on a carrier arm 22 and is rocked with respect thereto by an arm 23. The arms 22 and 23 are operated by well-known loom parts not set forth herein. The loom has a pull-over shaft 25 located above the fell of the cloth and having a step by step angular motion derived from known mechanism. There are two 35 transporting chains 26, one on each side of the loom, which extend upwardly and rearwardly in some such manner as that illustrated for instance in patent to Wyman and Hutchins No. 677,302, and indicated diagrammatically in Fig. 7.

The matter thus far described, except as modified hereinafter, may be constructed and operated in a manner similar to that found in previously known Axminster looms.

In carrying my present invention into effect I 45 secure to the under side of the top section 12 an L-shaped member 30 shown best in Fig. 1. The outer end of this member is bent upwardly to form a tongue 31 to extend between the members of the double link 32 of the transporting 50 chain. This member 30 may be secured to the transporting bar in any approved manner, as by means of screws 33, and there may be secured to the upper surface thereof at a point lying between the end of the carrier bar and the tongue 31 55

some form of spool bearing, such as that indicated at 35. The horizontal foot of this bearing may be welded to the member 30 while the vertical portion receives the gudgeon 21 and not only affords a bearing in which the spool may rotate but also holds the spool at a fixed distance from the carrier bar. The parts just described are fastened permanently to the carrier bar but are removable by means of the screws 33 when renewal of the spool bearing and tongue 31 is necessary.

The mechanism for detachably connecting the tube frame to the transporting chain is mounted for sliding motion longitudinally of the carrier bar and comprises a U-shaped slide 40 having top and bottom sections 41 and 42, respectively, which engage the undersides of the bracket member 30 and the top surface of the bottom section 13 of the bar, respectively. A compression spring 43 is interposed between the filler 16 and the vertical wall 44 of the slide and serves to push the slide outwardly.

The upper section 41 of the slide has welded thereto a rectangular hollow block or hook element shown at 50 in Fig. 2. This hook member is extended under the section 41 as at 51 and welded thereto, while the sides 52 extend upwardly and are connected together by a bridge 53 from one edge of which projects a supporting hook 54 shown for instance in Fig. 1. The outer edges 55 of the sides 52 engage the inner chain link 32 as shown in Fig. 1 to prevent the spring 43 from moving the slide out of the hollow bar. The lower section 42 is projected beyond the end of the carrier bar a considerable distance, as indicated at 56, and affords means by which the slide can be moved against the action of the spring to tube frame releasing position. In addition to the method already described to limit action of spring 43, I also project the tongue 31 high enough to engage hook 54, and this relation holds the slide in place when the tube frame is out of the loom.

The clutch C is formed with a vertical wall 60 from which projects a tongue 61 located a short distance above the floor 62 of the clutch. The latter has side wings 63 which are for the purpose of engaging the front and back vertical walls 14 and 15 of the bar to guide the latter and afford a control by which the tube frame may be moved angularly during the wiping-in and pulling-off operations when a row of tufts is being formed. The tongue 61 is located above the extended end 56 and the latter in turn is spaced slightly above the floor 62.

In the operation of the mechanism thus far described the chain is fed progressively with a step by step motion and comes to rest periodically in the position shown in Fig. 5 with one of the tube frames vertically under the pull-over shaft 25. At this time the spring 43 is holding the hook 54 yieldingly over the inner chain link 32 and the vertical edge 55 of the hook element is bearing against a chain link to prevent motion of the slide out of the hollow carrier bar. The tongue 31 is located between the links 32 as shown in Fig. 1 and the clutch is spaced from the slide. As soon as the transporting chain comes to rest the clutch will be moved inwardly by mechanism not shown but well understood and the tongue 61 will pass over the end 56 and the floor will engage the bottom 13 of the carrier bar to lift the same slightly for the purpose of relieving pressure between the hook 54 and the chain link on which it rests. Further inward motion of the clutch brings the vertical wall 60 into contact with the end 56 and preferably also against the

lower parts of the edges 55 of the hook element to move the slide inwardly to the dotted position shown in Fig. 1 against the action of spring 43. Both arms 41 and 42 of the slide are therefore pressed by the clutch, and the possibility of cramping is greatly reduced. This motion is considerably less than that of the clutch, but it is sufficient to move the hook 54 out of vertical alignment with any part of the transporting chain and the tube frame may therefore descend in the usual manner. During this descent the tongue 61 is over the end 56 and the latter is therefore closely confined between two horizontal parts of the clutch, namely, the tongue 61 and the floor 62. The tube frame is therefore controlled within narrow limits as to its vertical position by the clutch as the latter moves toward and from cloth forming position.

After the wiping-in and pulling-off operations of the tube frame the clutch is moved toward the chain and the tongue 31 enters between the links 32, upward motion continuing until the hook 54 is slightly above the top of adjacent link 32, whereupon the clutch will move outwardly or away from the center of the tube frame to permit spring 43 to reestablish holding connection between the chain and the hook 54.

An inspection of Fig. 1 shows that the point of attachment between the tube frame and the transporting chain is located at a point between the axis of the spool and the longitudinal axis of the carrier bar. As shown in Fig. 6 the arrow a represents the downward force due to the weight of the yarn spools while arrow b indicates the direction along which the weight of the carrier bar is exerted. The line C lies intermediate the top and bottom of the links 32 as viewed in Fig. 1, or between the hook 54 and the lower part of the tongue 31, for any and all positions of the tube frame as the latter moves along the loom overhead with the transporting chains. The location of line C can be so chosen as to lie substantially along the transverse center of gravity of the tube frame, the weight of the spool substantially balancing the weight of the tube frame. In one particular instance the loaded spools weigh approximately nine pounds while the carrier bar weighs approximately fifteen pounds and with such weights the location of the chain can be such that the center of gravity of the tube frame will pass through the chain link.

As heretofore constructed the chain has been in alignment with the spool axis and previous pull-over sprockets have been made accordingly. I find that by supporting the tube frame at a point intermediate the spool and carrier bar axes, more room must be allowed for the spools and the sprocket 70 is therefore of somewhat greater diameter than those heretofore employed. This sprocket may have a central web 71 with recesses 72 for the reception of tongues 31 and hooks 54. Projecting radially from the web between the recesses 72 are spaced plates 73 which receive the single links 74 of the transporting chain. The sprocket 70 may be secured to the pull-over shaft 25 in any approved manner and is given the aforementioned step by step motion to feed the tube frames one at a time to delivery position. The chain links are made correspondingly longer than those heretofore used.

Fig. 7 shows the overhead or transporting mechanism for the tube frames. The chains pass over sprockets 80 and under sprockets 81. When passing from one side to the other of a sprocket 80 the tube frame shifts somewhat relatively to

the chain, but the forces brought into play during the shift are reduced to a minimum by my invention.

From the foregoing it will be seen that my improved tube frame is so constructed that it is attached to the transporting chain at points lying between the spool axis and the longitudinal axis of the carrier bar. By this construction the weight of the spool is partly or completely balanced by the weight of the bar, depending upon the location of the hook and tongue, so that when passing along the overhead for the loom such turning strains as occur are greatly reduced. It will further be seen that the hook and tongue are located close to the longitudinal axis of the bar with the result that the distances through which the strains act is comparatively small. It will also be seen that the clutch preferably engages surfaces of the slide lying on opposite sides of the longitudinal axis of the bar for the purpose of preventing binding or cramping of the slide as it moves inwardly to release the tube frame. It will be seen that the sprocket and the chain are proportioned to permit suspension of the tube frame at a point between the spool and bar axes.

Having thus described my invention it will be seen that changes and modifications may be made therein by those skilled in the art without departing from the spirit and scope of the invention and I do not wish to be limited to the details herein disclosed, but what I claim is:

1. In a tube frame for an Axminster loom having a transporting chain, a hollow carrier bar, a hook member having parallel spaced arms slid-

able along interior surfaces of the bar, resilient means between the bar and the hook member tending to move the latter outwardly, the upper arm projecting beyond the end of the bar and having a chain engaging hook thereon, the lower arm projecting beyond the bar in position to be engaged for inward pressing, a tongue rigid with the bar to engage the chain, and a clutch having a floor and a projection spaced from and above said floor, said clutch movable to place 10 the floor below and the projection above the lower arm of said hook member and move the latter against the action of the resilient means to disconnect the hook from the chain.

2. In a tube frame for an Axminster loom having a transporting chain, a hollow carrier bar, a hook member slidable within the bar and having two spaced parallel parts the outer ends of which are separated from each other, a chain engaging element on one of said parts of the hook member, 20 the other of said parts to be pressed for detachment of the hook member from the chain, resilient means between the carrier bar and the hook member tending to move the latter outwardly to hold the chain engaging element in supporting 25 relation with respect to the chain, a tongue rigid with respect to the bar to engage the chain, a clutch to engage the second named part to move the hook member against the action of the resilient means, and a projection on the clutch to 30 enter the space between said parts and lie over the second named part.

ELBRIDGE R. HOLMES.
